UNITED STATES PATENT OFFICE.

OSCAR SODERSTROM, OF NORTH ATTLEBORO, MASSACHUSETTS, ASSIGNOR TO WHITTING & DAVIS COMPANY, A CORPORATION OF MASSACHUSETTS.

MANUFACTURE OF LINK MESH.

Application filed June 24, 1924. Serial No. 722,182.

This invention relates to the art of making link mesh fabric consisting of a plurality of links or rings, each of which is intermeshed with a plurality of other links. 5 More specifically, the invention relates to the production of pieces of link mesh of predetermined shape which are used in various commercial articles, such as ladies' hand bags, and the like. This invention includes 10 a piece of mesh of indefinite shape and outline in which pieces of a predetermined shape are so outlined that they may be easily removed therefrom, and further comprehends a method of producing such a 15 piece of mesh.

In the production of link mesh as carried on at the present time, machines are used which automatically insert links in the fabric, each link being formed of a length 20 of wire bent to ring form. These machines produce the mesh either in the form of a flat web or strip, or else in the form of a cylindrical sleeve which, upon removal from the machine, is cut lengthwise to form a 25 strip. In the utilization of these strips of mesh for the production of hand bags and other similar articles, pieces of appropriate form must be cut from the main strip of mesh and this has been done up to the 30 present in two ways, either manually or by machine. In the manual operation the workman places the strip of mesh on a table before him and then severs or spreads the links lying along the outline of the piece 35 which is to be produced. In determining the links which are to be acted upon, he refers to a pattern and locates the links which are to be severed or spread by counting along the rows of links from one edge of 40 the strip. When all of the links lying along the outline of the piece of the desired shape have been spread or severed, these links will drop or may be shaken out of the fabric so as to free the piece which is enclosed by 45 them, and these pieces are then used for the commercial products. In producing such pieces by machine, the strip of mesh is fed past a plurality of severing or spreading devices, of which there is one for each 50 link across the strip of the mesh, and these devices are controlled by a pattern mechanism. The strip and the devices have a relative step by step movement, and at each pause in the movement certain of the devices are rendered effective to act upon the

links to which they correspond in position. By continuing the step by step movement of the strip through the machine eventually all of the links in the outline of the piece of the desired shape are spread or severed, 60 and these pieces may then be freed from the strip of mesh by removing the outlining links. The manual or machine operations of producing such pieces are comparatively slow, and they add considerably to the cost 65 of the manufacture of the finished article. The manual operation is particularly laborious and tedious, and the workman may make mistakes in counting, which would result in loss by reason of the wrong link 70 being severed.

The present invention is intended to provide for the production of pieces of mesh such as are used commercially, by outlining these pieces in the main strip of mesh as it 75 is made by inserting in the strip of mesh at the appropriate points, links which differ in certain respects from those employed in the remaining portions of the mesh. These outlining links may be made of wire which 80 differs in appearance from the remaining links of the mesh, as for instance, an enamelled wire of some particular color may be employed for the purpose, and when the strip is removed from the machine these 85 outlining links may readily be distinguished from the other links of the mesh so that the manual operation of cutting is greatly simplified, since the counting of the links in the rows is eliminated. Instead of making 90 these links of a wire different in surface appearance, it is possible also to outline the pieces by means of links which differ in their mechanical properties from the links of which the remainder of the strip is made. 95 For instance, these outlining links may be made of wire of a comparatively soft metal so that the links may readily be spread apart. Then, when the strip is removed the operator will spread a few of these links 100 by hand and then, by pulling on the strip which is to be severed, can spread the remaining links in the outline, thus actually tearing the pieces from the main strip of mesh. By using for the outlining links wire 105 different either in appearance or in mechanical properties from the wire of which the other links in the strip are made, the separation of the commercial pieces is a simple and rapid operation, and the pieces may be re- 110

moved from the main strip without danger of severing the wrong links.

A strip of mesh having pieces of desired final form outlined in it by such readily removable links, may be made on any type of "sunset" mesh machine, such as are now in common use, provided such a machine is arranged so that the wire used in each link in the strip of mesh is under automatic control: "Sunset" mesh machines differ from ordinary mesh machines in that a plurality of different supplies of wire are provided and wire from any supply may be fed to the link-forming tools under the control of an automatic pattern mechanism by which the feeding of the wire from the different supplies takes place in a predetermined order of succession. These machines ordinarily include a pattern member of some form, as, for instance, a perforated music roll, and this pattern sheet has effective areas on it which are brought into action to control the wire-feeding devices, of which there is one associated with each supply of wire. In some of these machines the unit of control is a row or a part of a row of links across the web or around the sleeve. Consequently mesh produced on such a machine may have stripes or bands of links of different colored materials formed in it, but it is not possible to control the formation of each individual link as it is inserted. In other machines a pattern sheet is employed having an effective area for each link in the strip of mesh, and this pattern mechanism exercises its control in correspondence with the formation of each link so that any desired pattern, however elaborate, may be produced by properly forming the pattern sheet. It is this latter type of machine which is to be used in the production of pieces of mesh in accordance with the present invention, and as an example of this type of machine reference may be made to the machine illustrated in the co-pending application of Fred Sweeting, Ser. No. 722,708, filed June 27, 1924.

The machine as illustrated in that application produces "sunset" mesh in the form of a cylindrical sleeve and is provided with two sets of link-forming tools by which links are added at diametrical points on the sleeve. These tools add links in successive rows so that upon each complete rotation of the sleeve past the tools two rows of links are added at the edge of the sleeve. For each set of tools there are three supplies of wire and the machine is provided with a pattern control mechanism so arranged that wire from any selected supply may be fed to the tools for the production of each link. This machine, therefore, permits of the highest possible degree of control. In employing such a machine for the production of a strip of mesh in accordance

with the present invention, the wires from one of these supplies will be used for the links which are to outline the pieces used for the commercial articles. This wire may have a different surface appearance from that in the remaining supplies, as, for instance, it may be an enamelled wire of a color easily distinguished from the color of the other wires, or it may be a wire of different mechanical properties, preferably one which is quite soft so that the links formed from it may be easily opened up. It is to be understood, of course, that these outlining links only serve the purpose of connecting or uniting the pieces which are used for commercial purposes, and consequently the wire of which these connecting links are formed may be selected only with a view to its ready removability; it would be altogether possible to arrange the pattern sheet so as to cause it to prevent the link-forming tools from inserting links along the outline of the pieces of the predetermined shape, but this would seriously interfere with the operation of the machine since it would be impossible to move the strip of mesh through the machine if the strip were to be severed completely across, and in any event, the links on either side of the points where a link had been omitted would not lie in the proper position so that other links could be inserted through them. Outlining links must consequently be used in order that the operation of the machine may continue in the normal way, but, as before stated, these outlining links are eventually removed from the mesh and are made of a wire which is selected with that point in mind.

For a better understanding of the present invention reference will be made to the accompanying drawings, in which

Fig. 1 is a plan view of a portion of the strip of mesh produced on a machine, showing a piece such as is used for commercial purposes outlined in the strip by readily removable links,

Figs. 2, 3, and 4 are enlarged views of a piece of wire as used in the formation of a single link showing it in the different stages through which it passes under the action of the link-forming tools, and

Fig. 5 is a view of a piece of mesh such as is used commercially for the manufacture of a hand bag.

The strip of mesh illustrated in Fig. 1 has the form of a flat web and such a strip may be made on the machines either in the form shown, or else in the form of a cylindrical sleeve which is slit lengthwise and then opened out to web form. From this strip of mesh smaller pieces 7, as shown in Fig. 5, are to be cut for the production of commercial articles. The piece shown in Fig. 5 is one such as is used in a

hand bag and such a piece is attached along one end, as at 8, to the frame members of the bag, doubled upon itself, and joined along the edges 9 to complete the bag. If such a piece of mesh is to be produced by hand, the flat web 6 is laid upon the table and then the workman, referring to his pattern, will open or sever the links in the row 10 until he reaches the point 11. He must then sever links in the inclined row 18 until he reaches the edge of the strip at 13 and this severing of the links in the inclined row is a difficult and tedious operation since the operator must count the links accurately to determine which ones to cut. This operation of counting and severing is carried on around the outline of the piece and unless it is performed accurately the piece may be imperfect because the wrong links have been removed. When the operation is carried on by machine, the whole piece of mesh is fed through the machine and the tools which act on the links are brought into action at each successive row, the pattern mechanism causing the appropriate tools to act on the proper links in the several rows. This operation of pattern-cutting by the machine is also slow, but is considerably faster and more accurate than the hand method.

In accordance with the principles of the present invention, however, the machine on which the strip of mesh 6 is produced is so arranged that the tools operate to insert links along the outline of the piece 7 which are made from wire differing from the wire used in the other links in the strip. These outlining links may be made, for instance, of a wire having a different color, and the operation of inserting them is quite simple since it is only necessary to form the pattern sheet so that at the appropriate points the wire-feeding devices for the supply of this different kind of wire will come into action and feed wire to the tools. The mesh making operation for the production of the strip consequently continues in the normal manner until a strip of a convenient length is produced, which is then removed from the machine. The workman then takes the strip of mesh and severs the links in the outline of the pieces by means of a pair of scissors and since these outlining links are readily distinguishable from the other links in the piece, there is no difficulty in cutting along the outline. Instead of outlining the pieces for the commercial products by links having a different surface appearance from the other links of the fabric, it is also possible to make these outlining links of wire which differs in its mechanical properties from the wire used in the other links. It is preferable, for this purpose, to make use of a soft wire so that when the strip of mesh is removed from the machine the workman may tear the pieces from the strip by a manual operation and

without the necessity of cutting each of these links with scissors.

As another alternative, it is possible to make the strip of mesh mainly of links of a wire having a solder core, such, for instance, as shown in Fig. 2, in which the core is shown at 15. The piece of wire 16 is of a length such as is severed from the supply by the link-forming tools in the link-making operation, and this length, shown in Figs. 3 and 4, is first bent to the staple form and then after the legs of the staple have been inserted through a pair of links at the edge of the mesh the ends of the staple are bent together so that they abut, as shown in Fig. 4, thus completing the ring. Links of this solder-core wire are used throughout the fabric, being successively added in the usual way to produce a piece of mesh, a portion of which is illustrated at 14. The outlining links, however, are then made of wire which does not have the solder core, and to outline a piece such as is shown in Fig. 5, links of this plain wire are inserted, as at 17, then along the lines 18, 19, 20, 21, and 22. All of the links except those which lie in the outline of the piece are of the solder-core material, and the ends of the core in the ends of the links lie in abutment, as at 23. So-called soldered mesh is to be produced by this process, and the strip made mainly of solder-core links but having portions of a predetermined shape outlined by links of plain wire, is then subjected to a heating operation, such that the solder core softens and unites the ends of the links. Thus all of the links of the strip except those which outline the pieces to be removed therefrom, are of soldered or continuous links, while the outlining links are not soldered but are discontinuous. Upon the removal of the piece of mesh from the heating chamber, the discontinuous links may be spread apart by subjecting the mesh to a sufficient strain to cause these links to open up. The force which is necessary is by no means sufficient to open up the soldered links, and consequently, as before, the pieces for the commercial products may readily be freed from the main strip.

The present invention, therefore, provides a simple and effective method of producing pieces of mesh of a predetermined shape which is much less expensive than the manual and machine operations of pattern-cutting, as before described. The strip of mesh as it comes from the machine has pieces of the predetermined shape bounded by links which are readily removable and these links may be made of any kind of material desired, so long as it is different either in appearance or in mechanical properties from the remaining links of the fabric. These boundary links simply unite the pieces of the predetermined shape into a continuous

strip and once a strip of a convenient length has been completed and removed from the machine, these outlining links are to be removed so as to separate the pieces of selected 5 shape. The outlining links consequently perform no functions except to connect the pieces to facilitate their production by machine and to provide a convenient means of removing the pieces from the strip which 10 eliminates the expensive operations previously used. For these reasons, the outlining links may be made of any kind of wire differing in certain characteristics from the wire of which the other links of 15 the strip are formed.

I claim:

1. A strip of link mesh fabric composed principally of pieces of mesh having a predetermined shape such that the pieces are 20 adapted for separate use for commercial purposes, these pieces being outlined in the mesh by links of a composition different from that of which the links in the pieces are made, the links connecting the pieces to each 25 other and to the remainder of the mesh.

2. A strip of link mesh fabric composed principally of pieces of mesh having a predetermined shape such that the pieces are adapted for separate use for commercial 30 purposes, these pieces being outlined in the mesh by links of a metal different in its mechanical properties from the metals of which the links in the pieces are made, the outlining links serving to connect the pieces to each 35 other and to the remainder of the fabric.

3. A method of producing a piece of link mesh fabric of predetermined shape adapted for separate use, which comprises forming a strip of mesh of which the piece is a component part, and during the formation of 40 this strip inserting in it along the outline of the said piece links which connect the piece to the remainder of the strip and differ from those of which the piece is made.

4. A method of producing a piece of link mesh fabric of predetermined shape adapted for separate use, which comprises forming a strip of mesh of interengaging links and during the formation of the strip inserting 50 in it along the outline of the piece links which are readily distinguishable from those of which the piece is made and which connect the piece and the remainder of the strip.

5. A method of producing a piece of link

mesh fabric of predetermined shape adapted for separate use, which comprises forming a strip of mesh of interengaging links and during the formation of the strip inserting in it along the outline of the piece links of a material having mechanical properties different from those of the material of which the remaining links in the strip are made, the said different links connecting the piece to the remainder of the strip. 60

6. A method of producing a piece of link mesh fabric of predetermined shape suitable for separate use, which comprises forming a strip of mesh of interengaging links of which the piece is a component part, during the formation of the strip inserting in it along the outline of the piece links which differ from the links in the remainder of the strip and connect the piece to the remainder of the strip, and then removing these outlining links to free the piece from the strip. 70

7. A method of producing a piece of link mesh fabric of predetermined shape suitable for separate use, which comprises forming a strip of mesh of interengaging links of which the piece is a component part, inserting in the strip, during its formation, links of a material different from that of which the other links in the strip are made, the said different links being inserted along the outline of the piece and connecting the piece to the remainder of the strip, and then subjecting the strip of mesh to force applied so as to permit the ready removal of the outlining links, thereby separating the piece 80 from the remainder of the strip. 85

8. A strip of link mesh fabric composed principally of pieces of mesh having a predetermined shape such that the pieces are adapted for separate use for commercial 90 purposes, these pieces being outlined in the mesh by links of a metal more pliable than the metal of which the links in the pieces are made, the outlining links serving to connect the said pieces of mesh to each other 100 and to the remainder of the fabric.

9. A strip of link mesh fabric comprising a plurality of similar pieces of mesh each comprising a plurality of links, these several pieces of mesh being united by links of metal 105 softer than that of which the links in the pieces of mesh are made.

In testimony whereof I affix my signature.

OSCAR SODERSTROM.
